Henry C. Williams.

UNITED STATES PATENT OFFICE.

ALBERT C. LORD, OF NORTHFIELD, NEW HAMPSHIRE.

EYEGLASSES.

SPECIFICATION forming part of Letters Patent No. 322,461, dated July 21, 1885.

Application filed November 3, 1884. (No model.)

To all whom it may concern:

Be it known that I, ALBERT C. LORD, of Northfield, in the county of Merrimac and State of New Hampshire, have invented a new and useful Improvement in Eyeglasses, of which the following is a specification.

My invention relates to that portion of the eyeglasses known as the adjustable nose-piece; and it consists in an improved construction of the same, whereby the adjustability is obtained.

In the accompanying drawings, in which similar letters of reference indicate like parts, Figure 1 is a view in elevation of a pair of eyeglasses embodying my improvement. Fig. 15 2 is an enlarged view of one of the adjustable nose-pieces and adjacent parts. Fig. 3 is a section on line *x*, Fig. 2.

A is the spring or bridge, and B the spring 20 nose-pieces, secured to the eyes or bows C in the ordinary manner. The upper ends, B', of the nose-pieces are bent back, as shown, and instead of being provided with slots are simply perforated at *b*, (see Fig. 3.) such 25 perforations being large enough to allow the guide-pins D to extend loosely through them.

These guide-pins are pivoted at *d* to the free ends of brackets E, which are riveted at their opposite ends to the bows C, and are bent into the shape shown for the purpose of receiving 30 the guide-pins and allowing them to extend upward through the perforations in the nose-pieces.

It will readily be perceived that as the nose-pieces B are pressed away from each other in 35 adjusting the eyeglasses in position the guide-pins D swing back on their pivots and allow perfect freedom to the action and adjustability of said nose-pieces.

Having thus fully described my invention, 40 what I claim, and desire to secure by Letters Patent, is—

In eyeglasses, the combination, with the eyes or bows C, provided with the nose-pieces B B', perforated at *b*, of the guide-pins D, ex- 45 tending through said perforations and pivoted at *d* to the brackets E, substantially as and for the purpose set forth.

ALBERT C. LORD.

Witnesses:

ARTHUR T. CASS,

WM. T. CASS.
